UNITED STATES PATENT OFFICE.

FRANCIS W. GIBSON, OF WEST ROXBURY, MASSACHUSETTS, ASSIGNOR TO H. D. BEACH COMPANY, OF COSHOCOTON, OHIO, A CORPORATION OF OHIO.

DISPLAY-RACK.

1,314,796.

Specification of Letters Patent.

Patented Sept. 2, 1919.

Application filed May 7, 1919. Serial No. 295,382.

To all whom it may concern:

Be it known that I, FRANCIS W. GIBSON, a citizen of the United States, residing at West Roxbury, county of Suffolk, Commonwealth of Massachusetts, have invented certain new and useful Improvements in Display-Racks, of which the following is a specification.

This invention relates to a display rack for supporting rows of canistered goods with their covers foremost so that access may be readily had to the contents without removing the canisters from the shelves of the rack and without liability of upsetting the canisters or spilling the contents thereof.

According to my present invention the shelf structure itself is so modified as to provide canister guiding and confining portions which while permitting the free insertion and removal of the canisters from the shelves, positively define the canister positions and prevent the canisters from tipping as they are partially withdrawn and opened. In addition, my present rack is of neat and attractive appearance and provides for a maximum exhibition of the goods, and of the descriptive or advertising matter relating thereto, with a minimum of floor space.

The construction and use of my rack is described in the following specification and illustrated in the drawings forming a part thereof, throughout which like reference characters are correspondingly employed, and in the drawings:

Figure 1 is a front elevation of a display rack in accordance with my invention.

Fig. 2 is a side elevation thereof.

Fig. 3 is a vertical section.

Fig. 4 is a partial development of a shelf, and

Fig. 5 is a detail section particularly illustrating the manner of producing one of the guiding and confining portions for the canisters.

I have indicated at 1 spaced side members and at 2 a vertical series of spaced superposed hood-shaped shelves rigidly connecting said side members. The side members and shelves may be formed of any suitable sheet material.

The front edges of the side members may be inturned as indicated at 3 to eliminate sharp edges and to finish the appearance of the rack. The rear edges 4 of said members 55 and the bottom edges 5 are inturned as best shown in Fig. 1, to provide, respectively, stiffening and supporting flanges for the rack. The rack is open from front to rear and may be suitably braced, as indicated at 6. 60

The lowermost shelf of the series has a combined canister supporting and rack bracing function. The front edge of this shelf is down-turned and extends as a vertical bracing panel 7 secured to the bottom 65 edges of the side members 1 of the rack. The panel 7 also affords a relatively extended display surface for advertising matter. The top wall 8 of the rack has a down-turned stop flange 8¹ at its rear edge against 70 which the rear walls of the canisters C in the top row abut.

The intermediate shelves are preferably of one piece construction and in themselves contain the canister guiding and defining 75 function. As here shown, each shelf is formed as a rearwardly sloping bottom-forming wall 20 having an upturned back-forming wall 21 at the rear edge thereof, and a down-turned panel 22 at the forward 80 edge thereof, and having preferably at its junction with the back wall 21 one or more down-turned canister guide and bearing flanges 23. The bottom and back walls may also have attaching flanges 24 whereby the 85 shelves may be fastened to the side members 1 of the rack in connecting and bracing relation thereto.

The canister guiding flanges 23 may be conveniently formed by slitting the bottom 90 walls 20 of the shelves as indicated at 25 at substantially the line of fold (see the dotted line 26, Fig. 4) of the back-forming walls 21, and bending the tongues 23 thus produced backwardly, as indicated in dotted lines, 95 Fig. 5, until said tongues 23 lie in substantially the plane of the back-walls 21.

The tongues 23 are of sufficient length to bear upon the top rear portions of the canisters C beyond their centers of gravity whereby 100 to define the position of the canisters and prevent tipping thereof. In practice, the

tongues are found to function most satisfactorily when located in substantially the plane of the back-forming wall 21, although they may be located at any point 5 between two parallel planes, one of which passes through the front edge 22 of the shelf next below, and the other of which passes through the upturned rear flange 21 of said shelf, so as to overlie the top surface of the 10 containers at their overhang or displacement relative to the shelf.

The front flanges 22 of the shelves provide continuous horizontal panels for the display of advertising matter descriptive 15 of the goods, and the back walls 21 and flange 8¹ constitute stops which with the bottom walls 20 support the containers C in upwardly and outwardly inclined relation and with their covers L foremost, 20 whereby access may be had to the container contents without bodily removing the containers from the shelves.

If desired, an ornamental cap 9 may 25 surmount the top wall 8 to finish the appearance of the rack. As here shown, the cap 9 is of one piece construction, bent to suitable shape, and interlocked with the top wall 8 as indicated at 10, and riveted thereto as indicated at 11, Fig. 3.

30 Various modifications in the form and construction of my rack may obviously be made, within the limits of the appended claims.

What I therefore claim and desire to secure by Letters Patent is:

1. A display rack for supporting a row of covered containers in upwardly and outwardly inclined relation and with their covers foremost, comprising spaced side 40 members, and a shelf arranged therebetween and having a rearwardly sloping bottom forming wall and an upturned back forming wall, said walls at their junction cut-out to provide a downwardly extending portion disposed in guiding and confining relation to the containers whereby to define the position of the containers and to prevent tipping of a container when its cover is displaced to permit access to the contents 45 thereof.

50 2. A display rack for supporting a row of covered containers in upwardly and outwardly inclined relation and with their covers foremost, comprising spaced side members, and a shelf arranged therebetween and having a rearwardly sloping bottom forming wall and an upturned back forming wall, said walls at their junction cut-out to provide a downwardly extending tongue 55 disposed in substantially the plane of the back forming wall, and in guiding and confining relation to the containers whereby to define the position of the containers and to prevent tipping of a container when its 60

cover is displaced to permit access to the 65 contents thereof.

3. A display rack for supporting a row of covered containers in upwardly and outwardly inclined relation and with their covers foremost, comprising spaced side members, and a shelf arranged therebetween and having a rearwardly sloping bottom forming wall and an upturned back forming wall, one of said walls cut-out to provide a downwardly extending tongue 70 disposed between two parallel planes, one of which passes through the front edge of the shelf next below and the other of which passes through the upturned back-forming wall of said shelf, and said tongue disposed 75 in guiding and confining relation to the containers whereby to define the position of the containers and to prevent tipping of a container when its cover is displaced to permit access to the contents thereof.

4. A display rack for supporting a row of covered containers in upwardly and outwardly inclined relation and with their covers foremost, comprising spaced side members, and a shelf arranged therebetween and having a rearwardly sloping bottom forming wall and an upturned back forming wall, said bottom wall cut-out to provide a plurality of spaced downwardly extending tongues disposed between two parallel planes, one of which passes through the front edge of the shaft next below and the other of which passes through the upturned back-forming wall of said shelf, and said tongue disposed in guiding and confining relation to the containers whereby to define the position of the containers and to prevent tipping of a container when its cover is displaced to permit access to the contents thereof.

5. A display rack for supporting rows of covered containers with their covers foremost, comprising spaced side members, and a vertical series of spaced shelves arranged horizontally therebetween, said shelves having downwardly extending portions disposed between two parallel planes, one of which passes within the front edge of the shelf next below and the other of which passes through the rear edge of the shelf bottom, and said downwardly extending portions disposed in guiding and confining relation to the containers on the shelf next below whereby to define the position of the containers and to prevent tipping of a container when its cover is displaced to permit access to the contents thereof.

6. A display rack for supporting rows of covered containers with their covers foremost, comprising spaced side members, and a vertical series of spaced shelves arranged horizontally therebetween and comprising bottom and back forming walls, said walls

cut-out to provide downwardly extending portions disposed in guiding and confining relation to the containers whereby to define the position of the containers and to prevent tipping of a container when its cover is displaced to permit access to the contents thereof.

In testimony whereof I affix my signature in presence of two witnesses.

FRANCIS W. GIBSON.
